SPECTACLE FRAME

Maury Spencer, Virginia Beach, Va.

Application May 10, 1954, Serial No. 30,386

Term of patent 7 years

(Cl. D57—1)

FIG. 1.

The dominant feature of my design resides in the portions shown in full lines.

I claim:

The ornamental design for a spectacle frame, substantially as shown and described.
